UNITED STATES PATENT OFFICE.

HANS C. JORDHOY, OF NORTH PLAINFIELD, NEW JERSEY, ASSIGNOR TO WOOD NEWS-PAPER MACHINERY CORPORATION, OF NEW YORK, N. Y., A CORPORATION OF VIRGINIA.

THREE-ROLL INK MOTION.

Application filed June 15, 1926, Serial No. 116,072. Renewed July 25, 1928.

This invention relates to an inking device for rotary printing presses. The principal object of the invention is to provide an arrangement of ink distributing rolls of such 5 nature that the plate cylinders can be inked by three rollers without the necessity of employing a removable ink carriage.

Reference is to be had to the accompanying drawing which is a side view of a press 10 partly diagrammatic in form showing both inking systems, one of them on the right in the normal running position and the one on the left in the position assumed when the central roll is moved away from the plate 15 cylinder for any purpose.

Ordinarily in newspaper presses, two form rollers are employed for applying the ink to each plate cylinder. When more than two form rollers are used, as in the 20 case of magazine printing, it is necessary to have the ink motion roll away from the form in order to make it possible to remove the inside form rollers. The principal object of this invention is to avoid this and 25 eliminate the removable ink carriage heretofore thought necessary.

The invention is shown as employed with an ordinary ink fountain 10, fountain roll 11, pick-up roll 12, and distributing roll 13 30 receiving ink indirectly from the pick-up roll by another roll 14. The distributing roll applies the ink to a primary ink cylinder 15 which, by means of two transfer rollers 17 and 18, delivers ink to the secondary ink 35 cylinders 19 and 20. These ink cylinders transfer ink to the plate cylinder 21 by ordinary form rollers 22 and an intermediate form roller 23. In this case the form roller 23 receives ink from one of the ink 40 cylinders 19 the same as one of the form rollers 22. It is of smaller diameter so that irregularities of inking by either form roller will not be repeated on the plate cylinder in the same relation to those of the other. The other form roller 22 is the 45 only path through which ink is delivered from the ink cylinder 20 to the plate cylinder 21.

It will be understood that these various 50 rollers are geared together so as to rotate at desired surface speeds, which in ordinary cases are the same for all the rollers and equal to the surface speed of the cylinder 21. The gearing is not described in detail 55 as that is provided for in a well known way.

It will be seen that the frame 25 of the inking device which supports the fountain also supports directly the bearings for all these rollers except the roll 17. The ink cylinder 19 is supported in overhanging lugs 60 24 integral with the frame and projecting outwardly and downwardly. The bearings of the transfer roll 17 are mounted on frames 26 pivoted on the axis of the ink cylinder 15. A handle 27 is provided for 65 swinging this bearing frame 26 and a convenient means is provided for holding it in the position shown on the right in the drawings where it is in contact with the ink cylinder 19.

The roller 23 also is mounted in bearings 28 on the frame 25 from which it can be released and carried down by hand and swung around to the position on the left to get it out in front where it is readily 70 accessible. It is for this reason that the cylinders 19 are mounted on the overhanging lugs and the frame 26 is made to swing on the shaft of the cylinder 15 down into the position shown on the left in the drawing. This clears the way for the form 75 roller 23. A comparison of the positions shown on the right and left of the figure shows the whole motion and makes it clear that this exposure of the form roller 23 is 80 possible by this arrangement.

Although I have illustrated and described only one form of the invention and shown it as applied to a particular inking system, I am aware of the fact that it can be 85 applied to other systems and that modifications can be made by any person skilled in the art without departing from the scope of the invention as expressed in the claims.

Therefore I do not wish to be limited to 90 all the details of construction herein shown and described, but what I do claim is:—

1. In an ink motion, the combination with three form rollers, arranged to contact with a single plate cylinder, an ink cylinder for 100 delivering ink to certain of said form rollers, a transfer roller supplying ink to the ink cylinder, and means whereby the transfer roller can be moved away from its operative position to permit the inner one of 105 the two form rollers to be taken out through the space normally occupied by said transfer roller.

2. In an ink motion, the combination with two form rollers arranged to transfer ink to 110

the same plate cylinder, of an ink cylinder for supplying ink to both form rollers, a roller for transferring ink to the ink cylinder, and means for mounting the bearings 5 of the last named roller movably so that it can be moved bodily away from the ink cylinder to leave a space through which one of the form rollers can be removed.

3. In an ink motion, the combination with 10 a frame having overhanging lugs on its sides for supporting bearings, an ink cylinder supported in said bearings, and a removable form roller supported in such manner relative to the ink cylinder at the inner side of 15 said lugs for transferring ink from the ink cylinder to a plate cylinder that the form roller can be taken out around and under the ink cylinder.

4. In an ink motion, the combination with 20 a frame having overhanging lugs on its sides for supporting bearings, an ink cylinder supported in said bearings, a removable form roller supported at the inner side of 25 said lugs for transferring ink from the ink cylinder to a plate cylinder, and a roller for transferring ink to the ink cylinder, removably located near the bottom of the ink cylinder, whereby the form roller can be taken out around and under the ink cylinder.

5. In an inking system, the combination with 30 a plate cylinder, of three form rollers for delivering ink thereto, two ink cylinders together delivering ink to the three form rollers, transfer rollers for delivering the ink 35 to the ink cylinders, the central form roller being located between the ink cylinders and the outer transfer roller being mounted on a pivoted frame to swing down so that it will leave a space for the removal of the 40 central form roller.

6. In an inking system, the combination with 45 a plate cylinder, of three form rollers for delivering ink thereto, two ink cylinders together delivering ink to the three form rollers, transfer rollers for delivering the ink to the ink cylinders, the central form roller being located between the ink cylinders and being smaller than the others, one of said

transfer rollers being provided with a supporting frame pivoted at a distance from it 50 and capable of swinging with said transfer roller out of the path of the central form roller to permit removal thereof.

7. In an inking device for a web press, the combination with a fountain, a primary ink cylinder, and an ink fountain roll, pick-up 55 roll and distributing rolls for delivering the ink from the fountain roll to the primary ink cylinder, of a pair of transfer rollers in contact with said ink cylinder, two secondary ink cylinders in contact with the two transfer rollers for receiving ink therefrom individually, two form rollers in contact with one secondary ink cylinder and with the 60 plate cylinder, a form roller for delivering ink from the other secondary ink cylinder to the plate cylinder, the three form rollers being arranged around the circumference of the plate cylinder and one of them being located between the two secondary ink 65 cylinders and removable downwardly between them.

8. In an ink motion, the combination with 70 three form rollers, arranged to contact with a single plate cylinder, an ink cylinder for delivering ink to two of said form rollers, a transfer roller supplying ink to the ink cylinder, and means whereby the transfer roller can be moved away from its operative 75 position to permit the inner one of the two 80 form rollers to be removed.

9. In an inking system, the combination with 85 a plate cylinder, of three form rollers for delivering ink thereto, two ink cylinders together delivering ink to the three form rollers, transfer rollers for delivering ink to the ink cylinders, the central form roller being located between the ink cylinders, one 90 of said transfer rollers being provided with a supporting frame pivoted at a distance from it and capable of swinging with said transfer roller out of the path of the central form roller to permit removal thereof.

In testimony whereof I have hereunto affixed my signature.

HANS C. JORDHOY.
